UNITED STATES PATENT OFFICE.

THOMAS E. PENNELL, OF BROOKLYN, NEW YORK.

DESIGN FOR OIL-CLOTH.

Specification forming part of Design No. 11,135, dated April 1, 1879; application filed March 5, 1879.
[Term of patent 3½ years.]

To all whom it may concern:

Be it known that I, THOMAS E. PENNELL, of Brooklyn, county of Kings, State of New York, have originated and designed a new Pattern for Floor Oil-Clothes, Carpets, or other Fabrics, of which the following is a full, clear, and exact description, reference being had to the accompanying photographic illustration, making part of this specification, which fully represents said design, and is sufficient, without further aid, to enable any person skilled in the art to repeat it for practical use.

The colors employed for the different portions of this design may be varied to suit the convenience or taste of the manufacturer.

What I claim as my invention, and desire to secure by Letters Patent, is—

The design or pattern for floor oil-cloths, carpets, or others fabrics, as shown.

THOMAS E. PENNELL.
